UNITED STATES PATENT OFFICE.

WILLIAM KERR EDGAR, OF LAWRENCE, KANSAS, ASSIGNOR TO THE EDGAR STEEL SEAL AND MFG. CO., OF LAWRENCE, KANSAS.

AUTOMATIC FEED DEVICE.

1,344,492.

Specification of Letters Patent. Patented June 22, 1920.

Application filed August 29, 1919. Serial No. 320,598.

To all whom it may concern:

Be it known that I, WILLIAM KERR EDGAR, a citizen of the United States, residing at Lawrence, in the county of Douglas and 5 State of Kansas, have invented a new and useful Automatic Feed Device, of which the following is a specification.

This invention relates to feeding devices employed in connection with machines especially constructed for the purpose of cutting, stamping, punching or pressing rigid material in strap form into definite lengths; but more particularly to machines capable of operating on steel, iron or other metal, 15 capable of withstanding such treatment.

The primary object of the invention is to provide a feeding device of this character having means for automatically grasping and moving the metal strip under operation, 20 forward a predetermined distance under the operating tool of the machine, to insure predetermined uniform lengths, and sizes, being formed.

A further object of the invention is to 25 provide means of this character including a moving clamping element, which will tightly grasp the article or strap under treatment in such a way that the clamping element will not slip or move with relation 30 to the metallic slip.

With the foregoing and other objects in view, which will appear as the description proceeds, the invention resides in the combination and arrangement of parts and in the 35 details of construction hereinafter described and claimed, it being understood that changes in the precise embodiment of the invention herein disclosed may be made within the scope of what is claimed without departing from the spirit of the invention.

Referring to the drawings:—

Figure 1 illustrates a side elevational view of a metal working machine, with a feeding device constructed in accordance 45 with the present invention, attached thereto.

Fig. 2 is a perspective view of the controlling rod,

Fig. 3 is a top plan view of the feeding device,

Fig. 4 is a longitudinal sectional view through the carriage, showing the clamping jaw and operating lever, in elevation,

Fig. 5 is a sectional view taken on line 4—4 of Fig. 4.

Referring to the drawings in detail, the

reference characters 5 and 6 designate supporting blocks formed of any suitable metal or material, the same being relatively long and provided with cut-out portions 7 formed at the upper inner edges thereof, said cut-out portions extending the entire length of the members 5 and 6, and are closed by the relatively flat plates 8 secured to the supporting blocks 5 and 6 through the medium of bolts 9, extending through apertures 10 formed throughout the length of the plates 8, thereby providing a guideway.

Positioned within the cut-out portions of the supporting blocks 5 and 6, is the sliding carriage 11, which as shown, includes a 70 lower plate 12, having its side edges positioned in the cut-out portions under the plates 8, whereby the carriage 11 is permitted to move longitudinally of the supporting blocks, but is prevented from displacement therefrom, due to the close engagement between the carriage 11 and plates 8.

The lower plate 12, forming a part of the carriage, is recessed adjacent one end thereof, as at 13, and receives the lower portion 80 of the clamping frame 15, the same being provided with a central opening 16, in which is positioned the metallic jaw 17, the same being provided with a head 18 embedded within the lower plate 12 of the carriage 11, thereby preventing movement thereof with relation to the frame 15.

As shown, the clamping frame 15 is recessed as at 19 to form a guide way for the metal strip, which is being operated on by 90 the machine, the recess being partially closed by the upper member or plate 20, forming the upper portion of the clamping frame. This plate 20, is apertured as at 21, to provide a clearance for the vertically movable 95 elongated clamping jaw 22, the lower extremity of which is rounded as at 23 to permit of a free, unobstructed movement of the strip under operation, between the jaws.

Disposed above the lower plate 12, of the 100 carriage, is the upper plate 24 which is formed of metal or other suitable material, and which as shown is provided with a threaded opening 25 adapted to accommodate the threaded extension 26 of the tubular housing 27, which extends upwardly from the plate 24, and is provided with internal threads 28, formed throughout a portion of the length thereof, which threads accommodate the threaded adjusting nut 29, 110

for purposes to be hereinafter more fully described.

The threaded extension 26 is hollowed out as at 30, thereby providing a housing for the coiled spring 31, which embraces the upper portion of the jaw 22, directly under the circular cam supporting head 32, which head is provided with vertical ribs 33, engaging within slots 34 formed in the inner 10 wall of the tubular housing 27, for preventing rotary movement of the head 32, with relation to the casing 27.

The cam lugs 35, formed integral with the upper surface of the head 32, coöperate with 15 the cam lugs 36 formed on the under surface of the head 37, for causing a vertical movement of the elongate clamping jaw 22, in one direction, when the upper cam lugs 36 are moved, the coiled spring 30, returning the elongated clamping jaw to its normal or inoperative position, after the cam lugs 36 have been moved to disengage the cam lugs 35.

The cam shaft 38, is formed integral with 25 the cam head 37, and extends upwardly through the central opening 39, formed throughout the length of the adjusting nut 29, the upper end of said cam shaft 38 having connection with the operating trip-arm 30, 40, which extends laterally, for purposes to be hereinafter more fully described.

It is therefore obvious, that if the size or thickness of the material under operation is changed, the adjusting nut is rotated, there- 35 by moving the cam heads 32 and 37 within the tubular casing 27, whereby the distance between the clamping jaws 17 and 22 is regulated, to permit the same to effectively clamp the material under operation, when 40 the cam faces are brought together.

Stops 41 and 42, are also carried by the carriage 11, the same being positioned on the carriage within the path of travel of the arm 40, to engage the arm 40 and re- 45 strict the rotary movement thereof, to prevent the same from moving too far or during the clamping operation.

The upwardly extending lugs 43 and 44 are also carried by the plate 5, the same be- 50 ing supported at the respective ends of the plate 5, and are formed with openings 44' to receive the horizontally movable shaft 45, which carries the upwardly extending lugs 46 and 47, each of which being threaded to 55 receive the screws 48, which screws act as stops to engage the arm 40 when the carriage 11 is moved longitudinally of the guideway.

The forward end of the carriage 11, is 60 pivotally connected to the walking beam 50, of the machine, through the medium of the arms 49, of the walking beam 50, pivotally mounted at its fulcrum, on the brace or bracket 51, of the machine, while the upper 65 short or power end of this walking beam,

is pivotally and adjustably connected with the eccentric or crank of the stamping machine, or the rim thereof, through the medium of the pair of arms 52, the adjustable insert boxing 53, and the projection or 70 knuckle 54.

It will be observed that, as the walking beam 50 is actuated by the same eccentric or crank that operates the stamping guides, the vibrations will be absolutely synchronous, and more over as the carriage moves longitudinally in the guideway under the impulsion of the oscillating walking beam, it will by means of the elongated clamping jaw 22 and stationary clamping jaw 17, 80 alternately seize and release the strip of metal or other material as indicated in the drawings by the reference character 55, properly place the same under the machine, length by length, under the guides thereof, 85 said metal being prevented from backward movement in the carriage by the pilot, or spring pressed stop finger 56, supported adjacent the forward part of the machine, and disposed in a position to slide on the metal 90 and operate against the tension of the spring 57 operating in conjunction with the finger 56, the tension of the spring 57 being great enough to cause the finger to bite into the material under operation.

The larger adjustment of the device, or the adjustments which determine whether the material is to be two or ten, or any number of inches long, is effected by lengthening or shortening the upper or power arm 100 of the walking beam 50, by moving the insert boxing 53, up or down with its set screw; and as the power arm of this beam is relatively short, and the weight-arm long, it will appear that a very considerable 105 change in the amplitude of the carriage will be produced by only a slight change in the position of this insert boxing. But the more delicate and accurate adjustment, or the adjustment which determines the exact length, 110 no more or no less, of the strip under operation, is regulated by the trips or adjusting screws 48. These adjusting screws are, of course adjusted so as to correspond to the amplitude of the carriage or shoe in any 115 given case, as determined by the adjustment of the walking beam, but are always placed a little closer together, and within this amplitude, and exactly the length of the desired pieces apart, so that the carriage and its clamping jaws will always seize and release the strip of material under operation at points this precise distance from each other.

Pivots connected to the press head, is 125 the lever 58, the lower end thereof having pivotal connection with the lever 59, which has one corner thereof pivoted to the frame of the machine as at 60, to provide an eccentric, the upper end 61 thereof, having piv- 130

otal connection with the rod 45, through the rod 63 at one end thereof, as at 62, whereby vertical movement of the press head, causes a horizontal movement of the rod 45, with-
5 in the bearings or openings 44'.

This movement of the rod 45, is timed so that when the carriage 11 reaches the limit of its movement to the right, the adjusting screw 48 engages the arm 40 causing the 10 same to turn or move in a horizontal plane with the result that the elongated clamping jaw 22 is moved downwardly into engagement with the material under operation, which forces the same into engagement with the lower clamping jaw 17, this operation being accomplished by the coöperating cam lugs 35 and 36, carried by the respective heads 32 and 37.

It follows, that the return movement of 20 the carriage carries the material under operation under the press, or machine, and at the end of such movement the arm 40 engages the adjusting screw 48, at the opposite end of the machine, with the result that 25 the cam lugs 35 and 36, are disengaged. It follows that the coiled spring 31 forces the head 32 upwardly, disengaging the elongated clamping jaw 22 from the material under operation, whereupon the slide is free 30 to move to the opposite end of the guide way, where the operation is repeated.

Having thus described my invention, what is claimed is:—

1. In combination with the actuating device of a metal working machine, a guide way, through which the metal under operation moves, a carriage movable in the guide way, clamping jaws carried by the carriage, means for moving the carriage within the 40 guide way, means indirectly connected with one of the clamping jaws and extending laterally of the carriage, lugs within the path of travel of the carriage, adapted to engage the last mentioned means for causing a relative movement of the clamping jaws, and means for preventing reverse movement of the metal under operation.

2. In combination with the actuating mechanism of a metal working machine, a 50 guide way disposed adjacent the machine, and through which the metal under operation passes, a carriage movable in the guide way, said carriage supporting clamping jaws, an arm extending from one of said clamping jaws, means for moving the carriage, means within the path of travel of the carriage for engaging the arm for actuating one of said jaws, and means for preventing reverse movement of the metal under operation.

3. In combination with the actuating mechanism of a metal working machine, a 60 guide way disposed adjacent the machine, a carriage adapted to move in the guide way, a clamping frame carried by the carriage,

a stationary jaw carried by the clamping frame, a movable jaw coöperating with the stationary jaw, said jaws adapted to grasp the material under operation for moving the same predetermined distances, a lever, 70 means on one end of the lever for coöperating with means on the movable jaw for moving the same into coöperative relation with the stationary jaw, means for actuating the lever, and means for preventing 75 movement of the material under operation, in one direction.

4. In combination with the actuating mechanism of a metal working machine, a 80 guide way disposed adjacent the machine, a carriage operating in the guide way, means for moving the carriage longitudinally of the guide way, a stationary jaw carried by the carriage, a vertical jaw coöperating with the stationary jaw, the vertically 85 movable jaw having cam lugs provided thereon, an operating shaft having cam lugs thereon, said cam lugs adapted to coöperate to move the movable jaw, an operating arm having connection with the operating 90 shaft, and means for moving the operating arm, means for preventing rotary movement of the movable jaw, and means for preventing movement of the material under operation, in one direction.

5. In combination with the actuating mechanism of a metal working machine, a 95 guide way disposed adjacent the machine, a carriage operating in the guide way, means for moving the carriage, a tubular 100 casing supported by the carriage, a stationary jaw supported in the tubular casing, a vertically movable jaw coöperating with the stationary jaw, and operating through the casing, a head formed at the upper end of 105 the vertically movable jaw, cam lugs on the head, an operating shaft having a head formed at one end thereof, and carrying cam lugs coöperating with the first cam lugs for moving the movable jaw vertically in 110 one direction, means for returning the jaw to its normal position, means for operating the operating shaft at predetermined intervals, and a pilot for preventing reverse movement of the material under operation. 115

6. In combination with the operating mechanism of a metal working machine, a 120 guide way, a carriage movable in the guide way, means for moving the carriage, a stationary jaw supported on the carriage, and a movable jaw supported in the carriage, an operating shaft supported on the carriage, means on the operating shaft and coöperating with the means on the movable jaw, for moving the movable jaw in one direction, 125 means for adjusting the vertically movable jaw with relation to the stationary jaw, means for operating the operating shaft, and a pilot for preventing reverse movement of the material under operation. 130

7. In combination with the operating mechanism, of a metal working machine, a guide way, a carriage movable in the guide way, means for moving the carriage, a tubular casing, in the carriage, a stationary jaw supported in the carriage, a movable jaw positioned within the tubular casing, and co-operating with the stationary jaw, an operating shaft for moving the movable jaw
- 5 within the tubular casing, means for adjusting the operating shaft and movable jaw within the tubular casing, an operating arm for moving the operating shaft, and means

adapted to engage the operating arm, during the movement of the carriage, for moving the same in a horizontal plane, and means for preventing movement of the material under operation, in one direction. 15

In testimony that I claim the foregoing as my own, I have hereto affixed my signature in the presence of two witnesses. 20
